Attnys.

UNITED STATES PATENT OFFICE.

MOSES F. CARR, OF LEXINGTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed January 22, 1924. Serial No. 687,749.

This invention pertains to separable fasteners. It is among the objects of the invention to provide an efficient fastener having a socket of simple construction.

5 Referring to the drawings, which show two illustrative embodiments of my invention:—

Figure 1 is a front elevation of a preferred form of fastener;

10 Fig. 2 is a section on the line 2—2 of Fig. 1, being partly in elevation;

Fig. 3 is a section on the line 3—3 of Fig. 2;

Fig. 4 is an elevation of the socket as viewed from the attaching side;

Fig. 5 is a section similar to Fig. 2, but showing a modified form of my invention;

Fig. 6 is a detail section of the modified form shown in Fig. 5, and shows the means

20 for attaching the socket to the curtain; and

Fig. 7 is an elevation of the modified form of socket shown in Figs. 5 and 6 as viewed from the attaching side.

Referring to the drawings, I have shown 25 a stud of usual form, presenting a head 1, a neck 3 and a base 4, being attached to the fabric by a hollow rivet 2.

The socket 5 encloses a spring 6 of the simple "return bend" type, which is formed 30 from a single piece of wire providing adjacent its ends stud-engaging jaws 7. The casing of the socket is stamped from a flat sheet of metal and presents a front face 8 having an aperture 9 through which the stud 35 passes to engage the jaws 7. The aperture 9 is of a diameter only slightly greater than the major diameter of the head 1 of the stud and the inner face of this aperture lies so close to the neck of the stud as to permit 40 but relatively slight strain on the jaws 7 when the stud and socket are subjected to lateral strains in opposite directions.

The outer or encircling portion of the spring is supported by the peripheral wall 45 of the casing and the jaws are supported against transverse distortion on one side by the front face 8 of the casing and at the other side by the back face 10 of the casing. The back face 10 at an intermediate stage 50 of manufacture is generally perpendicular to the front face 8 and presents a series of tapered projections 11 which, after the spring has been placed within the casing, are folded inwardly to provide transverse 55 support for the jaws 7 and upwardly to pro-

vide attaching means for securing the socket to its carrying fabric. In Figs. 1 through 4, this attaching means constitutes a dome 12 providing interiorly a recess into which the head 4 of the stud may enter, as is best 60 shown in Fig. 2. This dome 12 has a central aperture through which a securing rivet enters, as is more fully hereinafter described.

By making the casing, as illustrated, with the foliated portion on that side which lies 65 adjacent the fabric, the front face 8 of the socket can be made as a continuous sheet of metal, and the aperture 9 may therefore fit the stud 1 so closely that lateral strains between stud and socket will be taken largely 70 by the socket casing. Thus the jaws 7 of the spring will not be subjected to such strains as might give a permanent "set" to the spring.

The socket shown in Fig. 2 is attached to 75 the fabric 13 by a rivet 15, which may be held in and concealed by the usual convex cap 14. The rivet 15 is of the tubular type, and may be slit or scored to facilitate upsetting the end. The upsetting tool is so 80 constructed as to apply very substantial pressure between the socket and socket-attaching cap adjacent their peripheral portions, during the upsetting of the tubular rivet, thereby to prevent possible spreading 85 of the foliated portions of the socket casing by the rivet-setting pressure. The end of the rivet passes through the fabric and then through the aperture in the dome 12 and the upset portions 17 of the rivet are clenched 90 against the shoulder 18 provided by flattening a portion of the dome 12, as is best shown in Figs. 2 and 3.

The term "fabric" as used throughout this 95 application is intended to include any suitable flexible carrying medium such, for instance, as cloth whether woven, knit or felt, and rubber, leather, paper and the like.

Referring now to Figs. 5 to 7, which illustrate a modified embodiment of my invention, the socket is substantially the same as the first described, except for the back face 10 which provides spring-holding ears 19, 19' overlying the upper and lower ends of the jaws 20. The spring-holding ear 19' is preferably, as illustrated, slit radially into three portions, of which the center portion is bent to project between the adjacent opposed portions of the spring to prevent turning of the spring relative to the socket casing. Be- 110

tween these two overlying ears, I have provided spaced apart prongs 21, which pierce the fabric 22 and are bent outwardly by the anvil surface 23 and are clenched against an inturned flange 24 of the attaching plate 25, as best shown in Fig. 6. The spaces between the prongs 21 may be serrated to present a rough edge to the fabric, thereby increasing the grip on the fabric which is exerted between the adjacent faces of the socket and attaching plate.

In the embodiment of my invention shown in Fig. 2, similar serrations may be provided by spurs 26 thrown down from the flange 15 of the tubular rivet 15.

The socket constructions illustrated are particularly useful where a notch 27 (Fig. 7) is provided at one side of the stud-receiving aperture to provide a lock between stud and socket against separation by the resolution of forces arising from lateral strain in a direction drawing the neck of the stud toward the notch, providing a fastener of the semi-locked type operating on the principles of the fastener shown in United States Letters Patent to Fred S. Carr No. 1,365,022, issued January 11, 1921.

While I have described in detail two preferred forms of my invention, it will be understood that I have done so for purposes of clarification and not of limitation. The scope of my invention is best defined by the appended claims.

I claim:

1. A fastener comprising a stud having a head and a neck in combination with a socket casing including in its formation a single piece of metal and presenting a back face formed from a series of inturned petal-like projections extending a substantial distance toward the center of the socket, a continuous peripheral portion, and a front face presenting an aperture closely fitting said neck, a spring of the return-bend type within said socket having jaws overlying a portion of said aperture to engage the neck of said stud.

2. A fastener comprising a stud having a head and a neck in combination with a one piece socket casing presenting a back face providing a dome formed from a series of inturned petal-like projections, a continuous peripheral portion, and a front face presenting an aperture closely fitting said neck, a spring of the return-bend type within said socket having jaws overlying a portion of said aperture to engage the neck of said stud.

3. A fastener comprising a stud having a head and a neck in combination with a socket presenting a one-piece casing having a peripheral wall, a front face integral with said wall and providing a stud-receiving aperture, a spring in said casing presenting a jaw intersecting said aperture to engage

said neck of said stud, and a back face formed from a series of tapered portions integral with said peripheral wall and folded toward the center of said casing to form a dome having an aperture to receive an attaching rivet.

4. In a separable fastener socket, a casing presenting an integral front face, peripheral wall and back face, the latter having a dome formed of infolded petals presenting an aperture through which an attaching rivet may be passed and the end of the rivet clenched against the inner surface of said dome.

5. A fastener socket presenting a casing having a continuous peripheral wall, a front face extending a substantial distance towards the center and there presenting a stud-receiving aperture, a spring in said casing presenting jaw means intersecting said aperture to engage the neck of a stud entered through said aperture, a back face integral with said peripheral wall and having a dome formed from a series of tapered portions to present a dome-shaped recess surrounding the head of the stud, and a hollow rivet for attaching said socket to a flexible carrying medium, said rivet passing through an opening in said dome and clenched within said dome over the ends of said series of tapered portions.

6. A fastener socket presenting a one-piece casing containing a spring, said casing having a front portion presenting a stud-receiving aperture, a peripheral wall portion and a back face, said back face including a series of laterally abutting infolded petal-like projections.

7. A fastener socket presenting a one-piece casing containing a spring, said casing having a front portion presenting a stud-receiving aperture, a peripheral wall portion and a back face, said back face having a rivet-receiving aperture and consisting of a series of laterally abutting infolded petal-like projections.

8. A fastener socket presenting a one-piece casing having a peripheral wall, a front face, and a back face including ears of substantial width extending a substantial distance toward the center of said casing, a return-bend spring presenting and engaging jaw portions having their ends overlain by said ears, said casing attachable to a curtain by upstanding prongs located between said jaw-supporting ears.

9. A fastener comprising, in combination, a stud having a head and a neck, a socket having a one-piece casing including a front face having a stud-receiving aperture therethrough, the periphery of said aperture presenting a notch for engagement with said neck when under lateral strain relative to said socket, said casing having a back face including a series of petals integral with

said casing for retaining said spring in said casing and for cooperation with a separate attaching part for securing said socket to a flexible carrying medium.

5 10. A fastener socket including a one-piece casing having a peripheral wall, a front face integral with said wall, a stud-receiving aperture through said front face, the periphery of said aperture presenting a notch, a back face including ears extending a substantial distance toward the center of said casing, a spring in said casing, and a spring-locating portion formed from one of said ears for locating said spring relative 10 to said notch.

11. A fastener attaching element part for application to the opposite side of a fabric from a separable fastener element for securing said second mentioned fastener element in position upon the fabric, said first mentioned element presenting, in combination, a cap, an attaching plate concealed within and secured to said cap, said plate presenting an attaching rivet for engagement with means presented by said second mentioned fastener element and a plurality of spurs for gripping the fabric interposed between the said two elements.

12. A fastener socket-attaching part for application to the opposite side of a fabric from a socket casing, said attaching part comprising, in combination, a cap, a tubular rivet presenting plate concealed within said cap, the edges of said cap being flanged inwardly to confine and hold the edges of said plate, said plate presenting, adjacent the inwardly flanged edge of said cap, a plurality of spurs for gripping the fabric interposed between said socket-attaching part and said 40 socket.

13. A fastener socket including a casing containing a spring presenting stud-engaging jaw portions, said casing presenting integrally therewith a peripheral wall, a front face, a back face, and a plurality of prongs extending from said back face for attaching said casing to a carrying medium, said back face including ears extending toward the center of said casing, to overlie the jaw portions of said spring, said prongs located between said ears and spaced apart to minimize weakening of the carrying medium by passage of said prongs therethrough.

14. A fastener socket including a casing presenting integrally therewith a peripheral wall, a front face, a back face, a plurality of prongs for attaching said casing to a curtain, said back face including ears extending

toward the center of said casing, said prongs located between said ears and spaced apart from each other to minimize weakening of the fabric by passage of said prongs therethrough, and fabric-gripping spurs in spaces between said prongs.

15. A fastener socket including a casing having a back face presenting a plurality of spaced apart prongs for socket-securing engagement with a cap located upon the opposite side of a curtain from the socket, and a plurality of fabric-gripping serrations located in one or more of the spaces between said prongs.

16. A fastener socket including a casing containing a spring having jaw presenting portions for engagement with a cooperating stud, said casing presenting at the back face thereof a support-engaging face adjacent the periphery, jaw-supporting means extended a substantial distance beyond the inner periphery of the support-engaging surface to overlie substantial portions of said jaw presenting portions at the back face to back-support said jaw presenting portions, and attaching means extended outwardly from said casing at the inner periphery of said support engaging face.

17. A fastener socket including a casing having a peripheral wall, a pair of spaced parallel faces extending inwardly from said wall to provide the front and back faces of the casing, a plurality of attaching prongs extended outwardly from the casing at the inner edge of the back or support-engaging face of said casing, and a relatively wide ear extending inwardly beyond said attaching prongs in a plane parallel with said back face.

18. A fastener socket installation including a carrying medium, a casing having a peripheral wall, a pair of spaced parallel faces extending inwardly from said wall to provide the front and back faces of the casing, a plurality of attaching prongs extending outwardly from the casing at the inner edge of the back or support-engaging face of said casing, and a prong-receiving plate located at the opposite side of the carrying medium, said prong-receiving plate presenting a support-engaging surface which cooperates with the support-engaging face of said casing to clamp the carrying medium tightly therebetween.

In testimony whereof, I have signed my name to this specification.

MOSES F. CARR.

CERTIFICATE OF CORRECTION.

Patent No. 1,651,340.

Granted November 29, 1927, to

MOSES F. CARR.

It is hereby certified that error appears in the printed specification of the above numbered patent requiring correction as follows: Page 2, line 37, claim 1, strike out the words "including in its formation" and insert instead "formed from", and line 39, strike out the words "formed from" and insert instead "including in its formation"; same page, line 117, claim 8, for the word "and" read "stud"; and that the said Letters Patent should be read with these corrections therein that the same may conform to the record of the case in the Patent Office.

Signed and sealed this 27th day of December, A. D. 1927.

Seal.

M. J. Moore,
Acting Commissioner of Patents.
